UNITED STATES PATENT OFFICE.

SAMUEL C. BALL AND JOHN J. GIBSON, OF CHICAGO, ILLINOIS.

RAILWAY-CROSSING.

SPECIFICATION forming part of Letters Patent No. 679,874, dated August 6, 1901.

Application filed December 21, 1900. Serial No. 40,631. (No model.)

To all whom it may concern:

Be it known that we, SAMUEL C. BALL and JOHN J. GIBSON, citizens of the United States, residing at Chicago, in the county of Cook and State of Illinois, have invented certain new and useful Improvements in Railway-Crossings, of which the following is a specification.

This invention relates to improvements in railway construction to be employed at the crossing of two or more railways; and it consists in certain peculiarities of the construction, novel arrangement, and operation of the various parts thereof, as will be herein-
15 after more fully set forth and specifically claimed.

The objects of our invention are, first, to provide railway-crossings which shall practically afford continuous rails on which the wheels of the train may travel, thus preventing the jolting incident to the passage of the wheels over the spaces between the adjacent ends of the intersecting rails, as is the case in crossings of the ordinary or general construction; second, to provide means whereby the main rails of the track may be made practically continuous by a device or devices carried by the locomotive or train, or said continuity of the tracks may be effected by hand
25 or the well-known interlocking system, and, third, to furnish a rotatable rail-section at the intersections of the main rails of the tracks which shall be so constructed that it will be self-lubricating, easily turned, and
30 securely held in position against accidental displacement.

In order to enable others skilled in the art to which our invention pertains to make and use the same, we will now proceed to describe it, referring to the accompanying drawings, in which—

Figure 1 is a plan view of a railway-crossing embodying our invention. Fig. 2 is an enlarged sectional view taken on line 2 2 of Fig. 1. Fig. 3 is a perspective view of one of the rotatable posts or shafts carrying a rail-section. Fig. 4 is a bottom perspective view thereof. Fig. 5 is a perspective view of the upper portion of a part of the bed-plate of the crossing; and Fig. 6 is a perspective view, partly in section, of a shoe secured to a portion of a locomotive.

Similar letters refer to like parts throughout the different views of the drawings.

A represents the main rails of one of the railway-tracks, and B similar rails of the intersecting track, while C represents the guard-rails. Located beneath said rails and supporting the same is a bed-plate D, which rests on and may be secured to the cross-ties in any suitable manner and which in the present instance we have shown as being sufficiently large to extend under the four intersections of the crossing; but we do not desire to be limited to such a construction, as we may use a separate bed-plate with our improved bearing for the rotatable post and rail-section at each of the intersections of the rails without departing from the spirit of our invention. At proper points to be located between the adjacent ends of the main rails of the tracks the bed-plate D is formed or provided on its upper surface with a circular boss or enlargement D', having a central opening d, through which the rotatable post extends, as is clearly shown in Fig. 2 of the drawings. One of these posts E is located in each of the openings in the bed-plate between the adjacent ends of the main rails, and each of said posts is provided on its upper portion with a circular disk E', having on its lower surface an annular flange e to form a recess e' for the reception and operation of the boss D' of the bed-plate. On the upper surface of each of the disks E' is diametrically located a rail-section E'', which extends upwardly, so as to be flush with the upper surface of the main rails. The circular disk E' on each of the rotatable posts is formed with an oil-chamber e'', the mouth of which may be closed by a suitable cover g, pivotally secured to the upper surface of said disk or circular portion. Extending from the lower portion of the chamber e'' is a channel or small opening e'', through which the oil or lubricant may escape. To prevent the oil or lubricant flowing too freely from the chamber, a quantity of packing or waste e'' may be placed therein to absorb and retain the oil. The lower portion of the post E is provided with a transverse opening e'' for the reception of a pin h, which is employed to hold the washer h' in position. Between the washer h' and the bottom of the bed-plate and surrounding

the post E is a spring h^2 , which serves to securely hold the rotatable post and rail-section in position, yet will yield sufficiently to allow the same to be freely turned.

5 In the drawings we have shown the rotatable post E, disk E', and rail-section E² as being made integral, and while we so prefer to construct said parts, yet we do not desire to be limited thereto, as we may construct them 10 separately and secure them together in any suitable manner.

In Fig. 6 of the drawings we have shown a shoe H, which is pointed at its front end and is secured by means of bolts g', passing through 15 an extension g² on the upper surface of the shoe to a portion G of the pilot of a locomotive or other portion of a train or locomotive.

In Fig. 1 of the drawings the shoes H are 20 shown by dotted lines as being located between the main rails B and guard-rails C and as traveling in the direction indicated by the arrows. When the train is traveling in said direction, it is apparent that the shoes H will 25 strike the rail-sections E² and turn them so as to be in alignment with the rails B, thus affording a smooth and practically unbroken track for the wheels of the train to pass over.

While we may use the shoes for the above- 30 described purpose, yet it is apparent that the flanges of the wheels when said shoes are not employed will strike the rail-sections and cause them to turn so as to be in alignment with the main rails of the track. It is also 35 evident that the rotatable posts carrying the rail-sections may be turned by other means than that carried by the locomotive or train by connecting them together.

Having thus fully described our invention, 40 what we claim as new, and desire to secure by Letters Patent, is—

1. In a railway-crossing, the combination of the intersecting main track-rails, with a bed-plate located beneath said rails and supporting the same, and having on its upper surface a boss formed with a central opening, said boss being located between the adjacent ends of the main track-rails, a rotatable post located in the opening of the boss on the bed- 45 plate, a disk on the upper portion of the post and having on its lower surface an annular recess to receive the boss, and a rail-section diametrically located on the upper surface of said disk, substantially as described.

2. In a railway-crossing, the combination 55 of the intersecting main track-rails, with a bed-plate located beneath said rails and supporting the same, and having on its upper surface a boss formed with a central opening, said boss being located between the adjacent ends of the main track-rails, a post rotatably located in the opening of the boss on the bed-plate, a disk on the upper portion of the post and having in its lower surface an annular recess to receive the boss, a rail-section dia- 60 metrically located on the upper surface of said disk, and a spring surrounding the lower portion of the post, substantially as described. 65

3. In a railway-crossing, the combination 70 of the intersecting main track-rails, with a bed-plate located beneath said rails and supporting the same, and having on its upper surface a boss formed with a central opening, said boss being located between the adjacent ends of the main track-rails, a post rotatably 75 located in the opening of the boss on the bed-plate, a disk on the upper portion of the post and having in its lower surface an annular recess to receive the boss, a rail-section dia- metrically located on the upper surface of 80 said disk, said post, disk, and rail-section being made of one piece, a washer secured on the lower end of the post, and a spring located around the post and between said washer and the bed-plate, substantially as described. 85

4. In a railway-crossing, the combination 90 of the intersecting main track-rails, with a bed-plate located beneath said rails and supporting the same and having on its upper surface a boss formed with a central opening, 95 said boss being located between the adjacent ends of the main track-rails, a post rotatably located in the opening of the boss on the bed-plate, a disk on the upper portion of the post provided with an oil-chamber and having in its lower surface an annular recess to receive the boss, a rail-section diametrically located on the upper surface of said disk, a washer located on the lower end of the post and a spring surrounding the post and located be- 100 tween said washer and the lower surface of the bed-plate, substantially as described.
